UNITED STATES PATENT OFFICE

120,610

DESIGN FOR A SINK SCOOP

Jenning T. Berge, Minneapolis, Minn.

Application March 16, 1940, Serial No. 90,997

Term of patent 14 years

To all whom it may concern:

Be it known that I, Jenning T. Berge, a citizen of the United States and residing in the city of Minneapolis, county of Hennepin, and State of Minnesota, have invented a new, original, and ornamental Design for a Sink Scoop, of which the following is a specification, reference being had to the accompanying drawing, forming a part thereof, wherein:

Fig. 1 is a perspective view of a sink scoop, showing my new design;

Fig. 2 is a top plan view of the sink scoop; Fig. 3 is a vertical section taken on the line 3—3 of Fig. 2 as indicated by the arrows; and

Fig. 4 is a view in front elevation of the sink scoop.

I claim:

The ornamental design for a sink scoop, substantially as shown.

JENNING T. BERGE.
